(57) **CLAIM**

The ornamental design for a diamond painting tray as shown and described.

DESCRIPTION

FIG. 1 is a perspective view of a diamond painting tray showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is another perspective view of the diamond painting tray showing my new design, in an alternate configuration. The broken lines depict portions of the diamond painting tray and form no part of the claimed design.

1 Claim, 9 Drawing Sheets
